MICRORAY VACUUM TUBE

André G. Clavier, Glen Ridge, N. J., assignor
to International Communications Labora-
tories, Inc., Newark, N. J., a corporation of
New York

Application February 29, 1932, Serial No. 595,765

3 Claims. (Cl. 250—27.5)

This invention relates to micro-ray signaling systems, and in particular to an improved vacuum tube for use in such a system, and a new combination of auxiliary apparatus to be used 5 with such a tube.

By micro-rays is meant electromagnetic waves the length of which lies approximately in the range between 1 and 100 centimeters.

In my U. S. Patent No. 1,928,408, granted No-
10 vember 26, 1933, I have disclosed a complete mi-
cro-ray signaling system including a particular
structure of tube for use therein.

In my U. S. Patent No. 1,959,092, granted May
15 22, 1934, I have disclosed a different species of
a tube for performing the same function.

In the tube disclosed in the latter patent, one
20 wire of a transmission line was connected to the
oscillating electrode and the other wire to the
reflecting electrode. The connection to the re-
flecting electrode battery was made from the cen-
tral point of the oscillating electrode.

If additional leads are provided for the reflect-
ing and oscillating electrodes and these leads ex-
25 tend from the tube in opposite directions to those
which lead to the transmission line, the tube is
easier to make, and a means is provided to de-
termine the state of oscillations of that extrem-
ity of the oscillating electrode which is away from
30 the transmission line. This may be done by pro-
viding a screening box which acts as a short cir-
cuit for the high frequency and modifies the state
of oscillations in the tube.

In the drawing:

Fig. 1 is a diagram of the micro-ray tube of
35 the present invention, connected at one side to
a micro-ray transmission line and at the other
side to leads to a local circuit, and enclosed in a
screening box;

Fig. 2 is a circuit diagram of the tube of Fig.
40 1 connected to a circuit for the production of
modulated waves; and

Fig. 3 is a circuit diagram of the tube of Fig.
45 1, connected to a circuit for detecting incoming
modulated waves.

In Fig. 1 a vacuum tube 1 has therein a stem
2 on which is mounted a reflecting electrode 3,
an oscillating electrode 4, and a filament or cath-
ode 5, as disclosed in my first-mentioned co-pend-
ing application. A screening box 6, with an ad-
50 justable lid 7, surrounds the tube. Leads 8 and 9
from the reflecting and oscillating electrodes, re-
spectively, are connected to a micro-ray transmis-
sion line 10 which may, in turn, be connected to
any suitable auxiliary apparatus, such as an an-
55 tenna, for transmission or reception of signals.

The reflecting and oscillating electrodes are also
connected to leads 11 and 12 which project from
the tube in opposite directions to leads 8 and 9,
and project through the lid 7 of the screening
box 6, from which at least one of them is insulated. 80
Filament 5 is connected to leads 13. When the
tube is being used for the transmission or recep-
tion of signals, the lid 7 of the screening box is
adjusted to a position where optimum results are
obtained. This position may be determined em- 85
pirically in each instance. For one adjustment
during the transmission of signals, it will be found
that the tube is more prone to oscillate and better
results are obtained. When signals are being re-
ceived, it will usually be found that a different 90
adjustment of the lid is necessary and a point will
be found where the tube will not oscillate, and
the received wave may be detected and amplified
without distortion. The radius of the screening
box should, ordinarily, be an odd multiple of an 95
eighth wave length, in order to avoid radiation
loss from the system, as disclosed in the first of
my patents referred to above.

When a shield is used, it prevents radiation
loss, as stated. However, the use of a shield is not 80
necessary for the operation of the invention. The
tube itself may be used for any purpose for which
any micro-ray tube may be used. The state of
oscillations within the tube may be controlled by
the use of a plane reflector at the position of the 85
plane portion of the lid 7 of the shield, in which
event the shield itself may be dispensed with.
The plane reflector will, of course, be adjustable
with respect to the leads 11 and 12, one of which
at least is insulated from said reflector. 90

In Fig. 2, a circuit is shown for the production
of modulated waves. An incoming modulating
signal is impressed on the transformer 14 across
which potentiometer 15 is connected. One end of
potentiometer 15 is connected to the filament 5, 95
while the other end is connected through a con-
denser 16 to the oscillating electrode 4. The os-
cillating electrode is also connected through a
choke coil 17 and a battery 18 to the filament 5.
The reflecting electrode 3 is connected through a 100
condenser 19 to a tap on the potentiometer 15,
which tap is adjusted to impress a definite portion
of the potential of the applied signal on the re-
flecting electrode and a definite portion on the
oscillating electrode, as disclosed in my co-pend-
ing application, U. S. Patent No. 1,962,582, granted
June 12, 1934. The filament is heated by battery
20.

In Fig. 3, which shows the tube of Fig. 1 con-
nected to a circuit for detecting and amplifying 110

received signals, a negative voltage is applied to the reflecting electrode by battery 21. The oscillating electrode 4 is connected to the filament 5 through a choke coil 22 and battery 23, which supplies this electrode with a positive potential. The primary of transformer 24 and the condenser 25 are also connected across the oscillating electrode and filament, and the detected signals may be received across the secondary of the transformer 24. The battery 26 heats the filament.

10 What is claimed is:

1. A micro-ray vacuum tube having a reflecting electrode, an oscillating electrode, and a cathode, said electrodes being concentrically disposed about said cathode, a pair of leads projecting from said tube connected to said reflecting and oscillating electrodes, a second pair of leads projecting from said tube in opposite direction to said first-mentioned pair of leads, also connected to said reflecting and oscillating electrodes, said pairs of leads being positioned substantially parallel to the axis of the concentric electrodes, and a shield housing said tube and the leads therefor, concentrically mounted with respect to the axis

of the electrodes and having a radius equal to an odd multiple of an eighth wavelength.

2. A micro-ray vacuum tube having a cathode, an oscillating electrode, and a reflecting electrode, a transmission line, leads from said oscillating and reflecting electrodes to said transmission line, leads from said oscillating and reflecting electrodes projecting from said tube in an opposite direction from said first leads, and a reflector through which said last-mentioned leads project and cooperate for adjusting the state of oscillations in said tube.

3. A micro-ray vacuum tube having a reflecting electrode, an oscillating electrode, and a cathode, leads for the cathode, two pairs of leads extending in opposite directions from said tube and connected respectively to opposite ends of the reflecting and oscillating electrodes, and means comprising a reflector co-operating with one of said pairs of leads and being adjustable along the length thereof for controlling the state of oscillations in said tube.
